UNITED STATES PATENT OFFICE.

SIDNEY HERBERT DONALDSON, OF HAMPSTEAD, ENGLAND.

ARTIST'S PAINT-BOX.

No. 825,266.

Specification of Letters Patent.

Patented July 3, 1906.

Application filed August 14, 1905. Serial No. 274,167.

To all whom it may concern:

Be it known that I, SIDNEY HERBERT DONALDSON, a subject of the King of England, residing at 6 Boundary road, Hampstead, in the county of London, England, have invented certain new and useful Improvements in Artists' Paint-Boxes; and I do hereby declare the following to be a full, clear, and exact description of the invention, such as will enable others skilled in the art to which it appertains to make and use the same.

This invention relates to a new and improved paint-box for artists' colors, and refers to means for facilitating the retention of water-colors or oil-paints in suitable receptacles for preserving and economizing the paint and rendering it more convenient to use same.

As is well known, it has been customary with artists' paint-boxes to keep the colors in collapsible tubes or open earthenware or metallic pans. This system is open to objection, since with the tubes of paint great waste occurs through the expulsion from the tubes of more paint than is required for immediate use, while with the open pans a considerable area of paint is exposed to the air, dust, and dirt. The water-color on the pan dries up in a short time and requires constant attention. With a paint-box made according to my invention these disadvantages are obviated, for in place of the collapsible tubes or open earthenware or metallic pans I store the paint in a series of rigid tubes of proper length and diameter made from pieces of tube fastened together or formed in a block of any suitable material. The tubes or tubular holes are fitted with suitable plungers for ejecting the paint through fine holes onto a suitable pallet, means being provided for sealing the holes when desired to prevent the paint drying up or being ejected when not required, and in order that my invention may be better understood I will now proceed to describe the same with reference to the drawings accompanying this specification, which show one method of carrying out my said invention.

In the drawings, Figure 1 shows a paint-box open. Fig. 2 shows side elevation of Fig. 1. Fig. 3 shows the same paint-box with the flap and cylinders containing the paint folded into the box. Fig. 4 shows a section of a portion of the cylinders, illustrating the means of sealing the said cylinders. Fig. 5 is a section along the line A B, Fig. 1. Fig. 6 shows end elevation of the portion of

the box containing the cylinders. Fig. 7 shows the lower portion of Fig. 5 on a larger scale.

The same characters of reference are employed to denote the same parts in all the views.

a shows body of the box, having hinged to it a cover portion *b*, provided with pallets for mixing the paint in the ordinary way.

c is the portion of the box containing the cylinders for the paint and is constructed in the following manner: *d* is a plate provided with convenient thumb-pieces *e* for holding the box during work. *f* is a metal strip soldered or otherwise suitably fixed at right angles to the plate *d*. *g* forms the back of this portion of the box, which is pivoted at *h* to the body *a*, the whole constituting a hinged member adapted to be folded within the body portion of the box. *i* represents holes bored at suitable intervals through the strip *f*, which forms the bottom of the cylinders. *j* shows cylinders which are provided with screw-threads at *k* and screwed into suitable collars fixed or formed on the strip *f*. The cylinders *j* are provided with pistons *m*, the rods *x* of which are screw-threaded to screw through holes *n* in the ends of the cylinders *j*. *o* represents knobs or milled heads at the ends of the rods *m*. *p* is a tube provided with holes corresponding in number and position to the holes *i* and also with holes *q*, which open into the channels *r* in the plate attached to the top of the cylinders. *s* is a rod which fits in the tube *p*, but can be slid into and out of same. *t* represents circumferential grooves in the rod *s* for the purpose hereinafter explained. *u* is a button or head to the rod *s* for facilitating the rotation and withdrawal of the said rod. The other end of the rod *s* is provided with a screw-thread *z*, which screws into a hole provided in the plate 2 at the end of the chamber formed between the strips *f* and *g*. *v* is a pivoted flap for covering the end of the space *w*.

The box is used in the following way: The cylinders *j* are filled with color, the rods *x*, carrying the pistons *m*, being of course screwed out of the cylinders *j*. The cylinders are then screwed into their respective collars on the strip *f*. When the rod *s* is screwed in or placed so that the grooves *t* come opposite the holes *i*, on screwing in the rod *x* and the piston *m* the color is expelled through the hole *i* in the strip *f*, through the hole in the tube *p* around the groove *t*, and through the

hole *g*, which forms a duct leading onto the channel *r* in the pallet-plate at the top. When the artist does not require the colors, the rod *s* is turned, slightly sliding it along in 5 the tube, so that the grooves *t* no longer come opposite the holes *i*, and consequently the paint in the cylinders *j* is cut off and air and dirt cannot obtain access to it. The space *w* is convenient for storing paint- 10 brushes, which can be kept in position by means of the pivoted flap *v*. It is evident that instead of having a number of tubes I may bore or otherwise form a number of parallel holes in a block of aluminium, earthen- 15 ware, vulcanite, or any other suitable material, with small holes extending from the cylinders thus formed to the outside flat surface through which the paint may be expelled.

What I claim is—

- 20 1. In an artist's paint-box, the combination with the body portion and hinged cover therefor, of a hinged member adapted to fold therein, and a plurality of hollow cylinders mounted on the hinged member, each being 25 provided with a piston and piston-rod, substantially as described.

2. The combination in an artist's paint-box, of a plurality of hollow cylinders, a tube mounted adjacent to the cylinders and provided with inlet-apertures communicating with the cylinders, and outlet-apertures, and a rod in said tube to regulate the flow of paint through said apertures, substantially as described. 30

3. The combination in an artist's paint-box, of a perforated plate, a tube extending longitudinally along one side of said plate and provided with apertures registering with the perforations of said plate, a plurality of collars on the opposite side of said plate encircling said perforations, a plurality of hollow cylinders connected to said collars, and a rod provided with circumferential grooves adapted to be brought into alinement with said apertures and outlet-apertures formed 40 45 in said tube, substantially as described.

In testimony whereof I affix my signature in presence of two witnesses.

SIDNEY HERBERT DONALDSON.
